WINDOW SASH SUPPORTING MEANS

Joseph Beller, Brooklyn, N. Y.

Application March 15, 1948, Serial No. 14,862

7 Claims. (Cl. 292—16)

1

This invention relates to window sash supporting devices and has particular relation to those supporting devices which without sash cords or weights will hold a window sash in any adjusted desired position.

The primary object of the invention is the provision of an improved window sash supporting means.

Another object of the invention is the provision of a window sash supporting means which will have a tendency to center the sash in a position to give each side the same clearance from the sides of the window frame, thus making it easier to start raising or lowering the sash.

Another object of the invention is the provision of an improved window sash supporting means wherein oppositely disposed rolling members engage opposite sides of an elongated member in a manner to retard the tendency of the sash to move until the operator desires it to be moved.

A further object of the invention is the provision of an improved window sash supporting means wherein oppositely disposed rotative means contact a fin which may be weather-stripping and retard relative movement between the window sash and its frame while still not preventing slight movement normal to the plane of the sash, thereby tending to prevent binding of the sash in the window frame.

A still further object of the invention is the provision of an improved window sash supporting means wherein a pair of oppositely disposed rotative members are held against an elongated fin by a single spring means in such a manner as to retard the movement of the sash until movement is desired by the operator.

Another and further object of the invention is the provision of an improved window sash supporting means wherein a main body member is provided with a pair of oppositely disposed rotative members having supporting means for supporting them in the holder in such a manner that they may grip a relatively stationary fin to prevent ready movement of the sash in the frame to open or shut the window but will allow slight movement of the sash substantially in the plane of the sash and normal to the plane of the sash while still retaining the rotative members in contact with the fin.

Other and further objects of the invention will be apparent to those skilled in the art from a reading of the complete specification.

Referring to the drawing wherein the invention is illustrated:

Fig. 1 illustrates a window having two sashes with my invention illustrated in place.

2

Fig. 2 is a section taken on the line 2—2 of Fig. 1 and showing the cross section of one modification.

Fig. 3 is an end view of my device showing a portion of the fin 14 taken on the line 3—3 of Fig. 4.

Fig. 4 is a cross section taken on the line 4—4 of Fig. 3.

Fig. 5 is a cross section taken on the line 5—5 of Fig. 3.

Fig. 6 is an end view of a modification shown in Fig. 8.

Fig. 7 is a sectional view of the form of the invention shown in Fig. 6 and taken on the line 7—7 of Fig. 8.

Fig. 8 is a section view of the form of the invention illustrated in Figs. 6 and 7 and taken on the line 8—8 of Fig. 7.

Throughout the specification and drawing, the same reference characters refer to the same and similar parts.

In Fig. 1, there is illustrated a window frame 10 having sashes 11. In the form of the invention illustrated, although not necessarily, there is illustrated a T-shaped member 12 attached to the window frame and a holder member 13 secured in the sash, as will be presently described in detail.

The T-shaped member 12 is provided with an outwardly tapered fin 14, the tapered construction being for a purpose to be described.

The housing or holder member 13 is illustrated at the top and left of the upper sash of Figure 1 and in Fig. 2, shown with its axis in the plane of the window sash. It will be understood that the sides of the sash 11 are provided with slots 15 throughout their lengths for coaction with the weather stripping such as the fin 14 of the T-shaped member 12 which serves as a slideway.

In the cylindrical side of the holding member 13 are two bearings to support the pivot member 16. On this pivot member 16, there is journalled a rotative member 17. Integral with this rotative member 17 is a sleeve extension 18. At the end of the extension 18 is a washer or flange 19. This washer or flange 19 may be made integral with the extension 18 by soldering or in any other suitable manner after the parts have been assembled.

Surrounding the extension 18 and freely movable therealong is the rotative member 20. Adjacent the extension member 18 and on the rotative member 20 is a hub 21 which tends to give stability to the rotative member 20. In order to normally have the rotative members 18 and 20 forced to

ward each other, there is provided a spring member 22. This spring 22 is held in place between the washer 19 and the side of the rotative member 20 and when in full operation, tends to hold the rotative members against the tapered sides of the fin 14.

It is to be here noted that there is a space between the extension 24 of the hub of the rotative member 15 and the housing member 13, and a similar space at the outer side of the washer 19. These spaces provide for a limited movement of the rotative member 17 together with the rotative member 20 and the spring member 22, along the pivot member 16. This movement may take place while still permitting the rotative members 17 and 20 to grip the fin 14. This construction which permits this free limited movement normal to the plane of the sash, tends to prevent the binding or sticking of the sash 11 in the window frame 10, yet holding the sash in the desired adjusted position. It will be noted that the adjacent sides of the rotative members 17 and 20 have a wiping action on the sides of the fin 14. This action on the fin is one which gives an excellent grip on the fin and consequently holds the sash in the desired position, until it is desired to place the window at another adjustment.

It is believed obvious that when the tension of the spring 22 is increased and the window moved, there will be a tendency of the spring 22 to move the rotative members toward each other and along the sides of the fin toward the tapered edge. With these units at opposite sides of the sash, this tendency of one unit to move toward the edge of the fin is counteracted by the action of the other unit at the opposite side of the sash. The tendency of each spring 22 is to move the sash, in its plane, away from the side of the frame at which the spring 22 is located. This is because of the tapered cross section of the fin 14. This tendency is counteracted by the action of the spring 22 at the opposite side of the sash. So that, if the sash is moved by hand, during raising or lowering, to a position farther, for example, from the left side, the spring on the right side tends to move the sash back toward the left side in the opposite direction to a condition where the two opposing springs 22 at opposite sides of the sash will be equally compressed. This, as already pointed out, is brought about by the taper of the fin 14 and the tendency of the rotative members 17 and 20 to work off of the edge of the taper as they turn, thus, each fin tending to force the sash to the opposite side. Thus an equilibrium is obtained with the sash tending to rest at equal distances from the opposite sides of the window frame. This central placing tends to make the window easier to start either in an up or a down direction.

In the drawing, suitable fastening means may be provided if desired but since these are not a part of this invention, per se, they have been indicated only in dotted lines.

In Figs. 6, 7 and 8 is illustrated a modification in which a housing member 30 is cut away and bent back to form an entry 31 for the fin 14. The pivot member 32 is secured in the opposite walls of the housing member 30. Mounted loosely on the pivot member 32 are a pair of complementary members 34 and 35 which are similarly constructed, the forward ends of the members 34 and 35 being provided with openings in which are secured loosely the rotatable members 36, which are spherical in shape and may be ball-bearings. For this purpose the outer ends of the members 34

and 35 are provided with oppositely disposed depressions 37 for the purpose of seating the balls 36. The openings through which passes the pivot member 32 are designated at 39 and are sufficiently large to permit of considerable movement of the members 34 and 35 on the pivot member 32.

The depressions 38 in the inner ends of the members 34 and 35 accommodate the spring member 39 which tends to push the outer ends of the members 34 and 35 apart. This action, due to the angularity of the members 34 and 35, tends to force the outer ends carrying the ball 36 towards each other. When in position to function with the fin 14 between the spherical members 37, the spring 39 will force the members against the fin 14. Due to the angularity of the members 34 and 35, the action of the members 34 and 35 on the fin 14 is similar to the action of the members 17 and 20 heretofore described.

The limited movement in a direction normal to the plane of the sash is taken care of by the openings 39 being larger than the pivot member 32. The centering action of the unit is due to the coaction of the spherical members 37 with the tapered sides of the fin 14 in a manner similar to the action between the rotative members 17 and 20 with the tapered sides of the fin 12a, as already described.

In Figs. 6 and 7, I have indicated by dotted lines the position of securing lugs 40 which may be added if desired. Since these securing means are not a part of this invention, per se, they will not be further described.

While I have shown and described my invention in detail, it is to be understood that the disclosure is merely illustrative and that modifications and changes may be made without departing from the spirit of the invention and within its scope as claimed.

This application is a continuation-in-part of my application, Serial Number 680,661, filed July 1, 1946, which is now abandoned.

Having described my invention, what I claim is:

1. An adjustable supporting means for maintaining a window member in adjusted relation to its frame member, comprising a slideway, and a second member relatively movable along the slideway, the slideway having two surfaces, the relatively movable second member having two relatively bodily movable axially rotatable members mounted thereon and resilient means for pressing the rotatable members axially in an endwise direction against the respective surfaces of the slideway, thus causing the rotatable members to rotate as the second member moves along the slideway.

2. An adjustable supporting means for maintaining a window member in adjusted relation to its frame member, comprising a slideway having fin means with oppositely facing sides, and a second member relatively movable along the slideway, the relatively movable member having a pair of axially movable rotatable members in position to engage the oppositely facing sides of the fin means and move therealong, and means for resiliently pressing the rotatable members axially in an endwise direction against the oppositely facing sides of the fin means to grip the same and thereby resist movement of the second member along the fin.

3. An adjustable supporting means for maintaining a window member in adjusted relation to its frame member, comprising a slideway having fin means and a second member relatively mov-

able along the slideway, the second member having a pair of substantially coaxially mounted rotatable members in position to engage oppositely faced sides of the fin and means for resiliently pressing the sides of the rotatable members against the fin.

4. An adjustable supporting means for maintaining a window member in adjusted relation to its frame member, comprising a slideway having fin means and a second member relatively movable along the slideway and having an axle member, a pair of rotatable members on and movable along the axle in position to engage two sides of the fin means, and a resilient means acting on the rotatable members to force a face of each against the fin means.

5. An adjustable supporting means for maintaining a window member in adjusted relation to its frame member, comprising a slideway having fin means and a second member relatively movable along the slideway, the fin means having two surfaces, the second member having an axle member mounted thereon, a pair of independently rotatable members mounted to rotate about the axis of the axle member, and each having a contact between its end portion and a surface of the fin means of the slideway and means for holding the rotatable members against the fin surfaces.

6. An adjustable supporting means for maintaining a window member in adjusted relation to its frame member, comprising a slideway having fin means, and a second member relatively movable along the slideway, the fin means having two surfaces, the second member having an axle member mounted thereon, a pair of independently rotatable members mounted to rotate about the axis.

of the axle member, and each in position to have a contact between its end portion and the fin of the slideway and a resilient means in position to cause a tendency of the rotatable members to approach each other and both rotatable members to approach one end of the axle.

7. An adjustable supporting means for maintaining a window member in adjusted relation to its frame member, comprising a slideway having fin means, and a second member relatively movable along the slideway, the fin means having two oppositely facing surfaces, the relatively movable member having a substantially cylindrical outer surface and having an axle member mounted in its wall, a rotatable member mounted for rotation on the axle, a second rotatable member mounted to rotate on the first-named rotatable member and a resilient means for forcing both rotatable members toward one side of the relatively movable member and toward each other and in position to frictionally engage the oppositely facing surfaces of the fin.
